(57) CLAIM

We claim the ornamental design for an inflatable L-shaped sofa, as shown and described.

DESCRIPTION

FIG. 1 is a perspective view of an inflatable L-shaped sofa;
 FIG. 2 is a front elevational view thereof;
 FIG. 3 is a rear side elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.

The broken lines in FIGS. 3, 4 and 7 represent portions of the inflatable L-shaped sofa that form no part of the claimed design.
